Inventor,
WILLIAM E. ROBERTS,
By *Mark & Litzinger* Atty's

UNITED STATES PATENT OFFICE.

WILLIAM E. ROBERTS, OF PORTLAND, OREGON.

SECTIONAL FURNITURE.

1,373,528.

Specification of Letters Patent.

Patented Apr. 5, 1921.

Application filed May 6, 1919. Serial No. 296,644.

To all whom it may concern:

Be it known that I, WILLIAM E. ROBERTS, a citizen of the United States, residing in the city of Portland, county of Multnomah, 5 and State of Oregon, have invented certain new and useful Improvements in Sectional Furniture, of which the following is a specification.

My invention relates to sectional furniture, and more particularly to new and useful means for interlocking or securing the sections together. It is common to build furniture and fixtures in sections, mounted one upon the other, and then set the vertical 15 units together. I have provided new and useful means for locking these vertical sections or uniting them to each other in such a way that they can be unlocked and separated or interchanged whenever desired.

20 In order to fully explain my invention, I have shown one practical embodiment of my invention in the accompanying two sheets of drawings, which I will now describe.

25 Figure 1 is a front elevation of three vertical tiers or units of sectional furniture secured together with my improved fastening means;

30 Fig. 2 is a top plan view of a base section;

Fig. 3 is a vertical sectional view through one of the vertical units, taken on line 3—3 of Fig. 1;

35 Fig. 4 is a fragmentary top plan view of two joined sections, at the joint and at the front edge of the top;

Fig. 5 is a perspective view of one of the front pilasters;

Fig. 6 is a detail of construction;

40 Fig. 7 is an end view of one of the intermediate sections with a part of the middle broken out to reduce the size of the figure; and

Fig. 8 is a fragmentary view of the two 45 ends of intermediate sections, showing my pilaster in front and one in the back, with connecting rod therebetween.

Referring now more in detail to the drawings, 1, 1, 1, designate three base sections, 50 2, 2, 2, designate intermediate sections adapted to set one upon the other, and 3, 3, 3, designate top sections. It will be understood that the general arrangement, size and number of intermediate sections 55 can be varied to meet the requirements. The base sections, 1, 1, 1, are set close to-

gether, one against the other, end to end. The top sections 3, 3, 3, are also set together end to end, as indicated in Fig. 4. The intermediate sections, are somewhat shorter 60 than the top and bottom sections to provide a space between the adjacent ends of intermediate sections of adjacent vertical tiers or units, as will be understood from Fig. 8, where two intermediate sections are shown 65 in fragmentary view. The base sections are provided in their tops, front and back, with pin-receiving holes 1^a, 1^a, while the top sections are provided in their under sides with similar holes, 3^a, 3^a. In the rear I provide a 70 back pilaster 4, provided in its opposite ends with pins, 4^a, 4^a, adapted to set into the holes in the base and top sections as the sections are placed together, as clearly indicated in Fig. 3. This pilaster extends from 75 the top of the base section to the bottom of the top section, as indicated and locks two adjacent base sections together, and also two adjacent top sections, as will be understood from Figs. 3 and 4. A double pilaster is 80 provided for the front, designated 5, shown in Fig. 5, and comprises a short section 5^a adapted to project between the spaced intermediate sections in the same manner that the back pilaster does, and is provided with 85 similar pins, 5^a, 5^a, in its top and bottom ends, as shown to interlock with the top and base sections in the same manner as do the pins in the back pilaster. Secured to said front pilaster, as a part thereof, is a front 90 piece which extends beyond the opposite ends thereof and overlies the adjacent base sections and also the adjacent top sections, as will be readily understood from Figs. 3 and 5. Said back and front pilasters are 95 provided on their inner faces with metal fastening members, 6, 6, provided with receiving slots, 7, 7, adapted to receive the connecting rods 8, 8, having nuts 9, 9, at their opposite ends. Thus the rear and front 100 pilasters are fastened together between the intermediate sections of the fixture and between the top and bottom sections thereof, as seen in Fig. 3. I also prefer to provide a spacing member 10 between the back and 105 front pilasters, detachably interfitting at its opposite ends with blocks 11, 11, secured to the inner faces of said front and back pilasters, as shown in Figs. 3 and 5.

Thus my top and base sections are made to 110 rest against adjacent top and base sections, end to end, and are secured together

by the insert pins in the back and front pilasters, as described. The intermediate sections are shorter than the top and base sections to provide space therebetween for 5 the pilasters, and for the connecting rods 8, and the spacing member 10. Any suitable interlocking means for the intermediate sections one upon the other can be used. I have shown the usual spaced bottom pieces, 10 12, 12 and the single top piece 13. When the sections are placed one upon the other, the spaced bottom pieces 12, 12 fit the opposite sides of the top piece 13 of the next section, as is well known.

15 What I claim and desire to protect by Letters Patent is,—

1. In sectional furniture of the character referred to, top and bottom sections for adjacent tiers of intermediate sections, and 20 intermediate sections one upon the other between the top and bottom sections, adjacent top and adjacent bottom sections resting against each other, end to end, and intermediate sections spaced apart to provide 25 a space between the intermediate sections and between the top and bottom sections, and a pilaster over the joint between adjacent tiers and having a shorter portion projecting between the ends of the intermediate 30 sections and constituting fastening means in said space securing adjacent top sections together and securing adjacent bottom sections together, substantially as shown and described.

35 2. In sectional furniture of the character referred to, vertical tiers of sections placed one upon the other and including in each tier base, top and intermediate sections, the intermediate sections being shorter than the 40 base and top sections, to provide space therebetween, the base sections of adjacent tiers and the top sections of adjacent tiers bearing end to end against each other, and locking means adapted to be inserted vertically 45 down into adjacent base sections and up into the undersides of adjacent top sections for locking adjacent base sections and adjacent top sections.

50 3. In sectional furniture of the character referred to, in combination, vertical tiers of sections set one upon the other, the base and top sections of each tier being longer than the intermediate sections thereof, whereby to provide a space between adjacent intermediate sections when two tiers are placed 55 together end to end, front and back pilasters arranged to extend from base to top sections between the intermediate sections, means on

the opposite ends of said pilasters adapted to be inserted into the tops of adjacent bottom sections and into the bottoms of adjacent top sections, and means for locking the back and front pilasters together. 60

4. In sectional furniture of the character referred to, in combination, vertical tiers of 65 sections set one upon the other, the base and top sections of each tier being longer than the intermediate sections thereof, whereby to provide a space between adjacent intermediate sections when two tiers are placed 70 together end to end, front and back pilasters having pins in their opposite ends adapted to be inserted down into the tops of adjacent bottom sections and up into the bottoms of adjacent top sections for connecting adjacent top sections together end to end and adjacent bottom sections together end to end, the front pilaster having a front portion extending from the bottom of the base section to the top of the top section, substantially as described. 75

5. In sectional furniture, in combination, base, intermediate and top sections set one upon the other, the intermediate sections being shorter than the top and base sections, 80 whereby when two tiers of sections are placed together base sections and top sections of adjacent tiers adjoin each other, means for interlocking adjacent base sections and adjacent top sections together end 85 to end, said means comprising pins adapted to be inserted down into the tops of adjacent base sections and up into the bottoms of adjacent top sections, substantially as described. 90

6. In sectional furniture, in combination, base, intermediate and top sections set one upon the other, the top and base sections having projecting parts at their ends, whereby they are longer than the intermediate 100 sections, providing a space between the ends of the intermediate sections of two tiers, and means connecting the tops of the projecting portions of adjacent base sections and means connecting the bottoms of the 105 projecting portions of adjacent top sections, whereby adjacent tiers of sections are interlocked together at their base and top sections.

Signed at Portland, in the county of 110 Multnomah, and State of Oregon, this 21st day of April, 1919.

WILLIAM E. ROBERTS.

In presence of—

NATHAN A. BOODY,
JOHN R. GRIFFITH.
